GAS MIXING METHOD AND BLOWPIPE APPARATUS

John Villoresi, Lincoln Park, and Arthur P. Scheller, Union, N. J., assignors, by mesne assignments, to Union Carbide and Carbon Corporation, a corporation of New York

Application August 20, 1948, Serial No. 45,235

7 Claims. (Cl. 158—27.4)

1

This invention relates to method and apparatus for mixing combustion supporting and fuel gases in a blowpipe head.

The conventional mixing of such gases is by means of a nozzle located somewhere in back of the head of the blowpipe, generally in one of the connecting tubes between the handle and the head. With this arrangement the particular mixer required a particular nozzle, and the blowpipe was subject to flashbacks.

Objects of the present invention are to provide a blowpipe mixer in the blowpipe head, to improve the mixing of the gases in the blowpipe, to adapt the blowpipe for interchangeable nozzles, and to improve the flashback resistance of the blowpipe.

Other objects and features of novelty will be apparent from the following description and the accompanying drawings, in which:

Figure 1 is a vertical cross section through a blowpipe head, showing apparatus according to, and for carrying out the method of the present invention; and

Figure 2 is a perspective view of the mixer employed in the blowpipe head of Figure 1.

The apparatus shown in the drawing comprises a blowpipe head H having an inlet O for cutting oxygen, an inlet A for fuel gas such as acetylene, and an inlet P for preheat oxygen. The head H has a cavity C of stepped bores respectively communicating with the gas inlets, and receiving a mixer M of correspondingly stepped diameters. The mixer M in turn has stepped bores which correspondingly receive stepped diameters of a nozzle N. The spacing of the interfitting portions of the cavity, mixer and nozzle leaves annular chambers through which the fuel gas and preheat oxygen pass and effect commingling thereof to form the preheat mixture. The head mixer and nozzle have aligned central drillings forming a continuous straight central passage for cutting oxygen.

The cavity C comprises an upper inner bore 10, an intermediate bore 12, and a lower outer chamber 14. A conical seat 13 is provided between the bores 10 and 12, and another conical seat 15 is provided between the chamber 14 and the outer end of the cavity C.

The mixer M comprises an upper smaller end 20 entering the bore 10, an intermediate portion 22 entering the bore 12, and a skirt 24 entering the outer end of the cavity C, with intermediate conical seats 23 and 25 respectively engaging the cavity seats 13 and 15. The smaller end 20 is grooved to receive a ring sealing washer 20

26 for engaging the bore 10 in the head H. The annular shoulder at the top of the intermediate portion 22 is spaced with respect to the seats 23 and 25 to form the upper part of the bore 12 into an annular fuel gas entrance chamber which receives acetylene from the inlet A.

The diameter of the intermediate mixer portion 22 is less than the bore 12 by a small clearance of the order of ten thousandths of an inch or less, leaving a narrow annular channel therebetween extending from the acetylene inlet chamber to the preheat oxygen inlet chamber 14 which receives preheat oxygen from the inlet P which is preferably concentric with the acetylene inlet A. The skirt portion 24 of the mixer engages a ring seal washer 27 received in an annular groove formed in the cavity C below the seat 25.

The interior of the mixer M has stepped bores similar to the cavity C, and the nozzle N has stepped diameters similar to the outside of the mixer, with conical seats therebetween, defining a nozzle entrance preheat mixture chamber 30. Angularly spaced downwardly inclined drillings 32 through the mixer M connect the center of the narrow mixing passage with the chamber 30 which in turn distributes the preheat mixture to the nozzle preheat passages 34.

The nozzle N has a central cutting oxygen passage 35, and the mixer M has a central passage 36 aligned therewith, and communicating with the cutting oxygen inlet O.

In operation, fuel gas such as acetylene passes from the inlet A into the acetylene inlet chamber formed by the inner end of bore 12 and the shoulder of the mixer portion 22 and starts down the narrow mixing passage between the bore 12 and the mixer portion 22. At the same time, preheat oxygen from the inlet P passes downwardly into the lower outer chamber 14 and then with an abrupt reversal of direction starts up from the bottom of the annular mixing passage between the bore 12 and the mixer portion 22. The descending narrow annular stream of fuel gas meets the ascending narrow annular stream of preheat oxygen head-on, midway between the ends of the mixing passage, and the impact of the collision within such narrow confines creates maximum turbulence and consequent thorough intermingling of the gases to form the preheat mixture. The mixture thus formed passes downwardly and inwardly through the drillings 32 to the nozzle entrance preheat mixture chamber 30, which distributes it to the nozzle preheat passages 34.

The cutting oxygen from the inlet O passes through the bore 10 and mixer passage 36 to the nozzle cutting oxygen passage 35 .

What is claimed is:

1. Method of mixing combustion supporting and fuel gases in a blowpipe head which comprises introducing the gases to be mixed into separate axially spaced annular chambers, directing annular streams of the gases from said chambers toward each other in a narrow confined annular path whereby the gases meet head-on intermediate the ends of said annular path, and directing the mixed gases from intermediate the ends of said annular path to the blowpipe nozzle.

2. Method of mixing combustion supporting and fuel gases in a blowpipe head which comprises introducing the gases to be mixed into separate axially spaced annular chambers, directing annular streams of the gases from said chambers toward each other, confining said streams in a narrow annular path to localize the mixing zone, whereby said annular streams impact each other intermediate the ends of said narrow annular path, and directing the mixed gases from intermediate the ends of said annular path to the blowpipe nozzle.

3. Method of mixing combustion supporting and fuel gases in a blowpipe head, which comprises directing an annular stream of the combustion supporting gas in a narrow confined annular path in a direction axially of the blowpipe nozzle toward the nozzle outlet, directing an annular stream of the fuel gas to be mixed in the same narrow confined annular path but backward in the opposite direction away from the nozzle outlet whereby the gases meet head-on intermediate the ends of said annular path, and directing the mixed gases from intermediate the ends of said annular path to the blowpipe nozzle, whereby said backward flowing fuel gas is subjected to an abrupt reversal of direction during the mixing operation tending to minimize flashback.

4. A blowpipe head having a cavity and spaced inlets for oxidizing and fuel gases, and a mixer in said cavity, a nozzle received in said mixer, said head and mixer having contacting portions forming longitudinally spaced annular seats, said head and mixer also having registering recesses between said seats forming longitudinally spaced annular inlet chambers respectively connected to said inlets, said registering recesses also forming a narrow annular throat between said inlet chambers, said mixer having a passage therethrough leading from a zone intermediate the ends of said annular throat to said nozzle.

5. A blowpipe head having a cavity and spaced inlets for oxidizing and fuel gases, and a mixer inserted in said cavity and having annular grooves registering with corresponding portions of said cavity to form annular chambers com-

municating respectively with said inlets, said mixer and cavity between said grooves being spaced apart to form a narrow annular passage between said chambers, said mixer having a cavity, a nozzle received in said inner cavity, and passages formed therein leading from said narrow passage through said mixer to said nozzle, whereby the gases from said respective inlet chambers flow toward each other from opposite ends of said narrow passage and meet head-on therein before flowing out through the mixer to the nozzle.

6. Apparatus for mixing combustion supporting and fuel gases in a blowpipe head which comprises means forming separate axially spaced annular chambers, inlets formed in said head for introducing the gases to be mixed into said separate axially spaced annular chambers, a narrow confined annular path formed in said blowpipe head for directing annular streams of the gases from said chambers toward each other, whereby the gases meet head-on intermediate the ends of said annular path, and passages formed in said blowpipe head for directing the mixed gases from intermediate the ends of said annular path to the blowpipe nozzle.

7. Apparatus for mixing combustion supporting and fuel gases in a blowpipe head, which comprises a mixer cooperating with said blowpipe head to form a narrow confined annular path, said mixer having a cavity, a nozzle received in said mixer cavity, said blowpipe head and mixer having portions cooperating to direct an annular stream of combustion supporting gas in a direction axially of the nozzle toward the nozzle outlet, said blowpipe head and mixer having portions cooperating for directing an annular stream of fuel gas in the same narrow confined path but backward in the opposite direction away from the nozzle outlet whereby the gases meet head-on intermediate the ends of said annular path, and said head having passages for directing the mixed gases from intermediate the ends of said annular path to the blowpipe nozzle, whereby said backward flowing fuel gas is subject to an abrupt reversal of direction during the mixing operation tending to minimize flashback.
